UNITED STATES PATENT OFFICE.

SIMON FINKELSTEIN, OF BROOKLYN, NEW YORK.

COLLAPSIBLE BOX.

1,101,019.

Specification of Letters Patent. Patented June 23, 1914.

Application filed September 5, 1913. Serial No. 788,220.

To all whom it may concern:

Be it known that I, SIMON FINKELSTEIN, a citizen of the United States, residing at Brooklyn, in the county of Kings and State 5 of New York, have invented certain new and useful Improvements in Collapsible Boxes; and I do hereby declare the following to be a full, clear, and exact description of the invention, such as will enable others skilled in 10 the art to which it appertains to make and use the same.

My invention relates to new and useful improvements in collapsible boxes that are particularly adapted for shipping purposes.

15 An important object of my invention is to provide a collapsible box which, when not in use may be folded and secured in a folded position so as to take up little room when shipped.

20 An equally important object of my invention is to provide a box that is constructed and arranged to withstand great shocks and is reinforced when in an open position by a bolt or bolts so arranged as 25 not to interfere with the articles contained in the box.

A still further object of my invention resides in the provision of a novelly constructed lid for my box that is provided with 30 ventilating means and adapted to be secured to the box when the box is in its folded position.

An object of equal importance is to provide a box such as described which is simple 35 as to construction and arrangement of parts as well as durable and light and cheap to manufacture.

The above and additional objects are accomplished by such means as are illustrated 40 in the accompanying drawings, described in the following specification and then more particularly pointed out in the claims which are appended hereto and form a part of this application.

45 With reference to the drawings, wherein, I have illustrated the preferred embodiment of my invention as it is reduced to practice, and throughout the several views of which, similar reference numerals designate corresponding parts: Figure 1 is a perspective view of my improved box in assembled operative position, Fig. 2 is a top plan view with the cover removed, Fig. 3 is a plan view of the under side of the cover illustrating 50 the ventilating means attached thereto, Fig. 4 is a perspective view of a slightly modified

form of my box illustrating the side and end walls thereof formed of hinged sections, Fig. 5 is a cross sectional view taken on line 5—5 of Fig. 1 illustrating my box as it 60 would appear when in a folded position, Fig. 6 is a cross sectional view of the form of my box illustrated in Fig. 1 showing it as it would appear in folded position, Fig. 7 is a detail perspective illustrating the catch 65 for holding the side and end walls in proper position, and Fig. 8 is a cross sectional view taken on line 8—8 of Fig. 4 illustrating the box such as disclosed in Fig. 4, as it would appear in folded position.

The box of my improved construction 70 consists of the bottom wall 1, front and rear walls 2 and 3 respectively, and side walls 4 and 5. A plurality of molding strips 6 are secured to the edges of the bottom wall 75 1 and serve to reinforce the construction of the box. The side walls 4 and 5 are hingedly secured to the bottom wall 1 and are adapted when folded, to lie flat against the upper surface of the bottom wall 1. 80 Strips 7 and 8 are suitably secured in a vertical position to the front and rear edges of the bottom wall 1. The front and rear walls 2 and 3 are hingedly secured to the strips 7 and 8 so as to lie when folded, against the 85 upper surface of the side walls 4 and 5, which are to be folded before the front and rear walls 2 and 3 when it is desired to fold the box. Flanges 9 and 10 are carried upon the terminals of the front and rear 90 walls 2 and 3 and strips 7 and 8. These flanges 9 and 10 extend inwardly beyond the inner faces of the walls 2 and 3 and strips 7 and 8 and are secured in any suitable manner or formed integral with the 95 walls 2 and 3 and strips 7 and 8.

A plurality of catches 11 are arranged upon the inner faces of the walls 2 and 3 adjacent the upper edges thereof. These catches 11 consist of beveled face blocks that are secured in any suitable manner to the 100 walls 2 and 3 after the manner described.

Assuming the box to be in a folded position such as illustrated in Figs. 5 and 6 in the drawings, when it is desired to open the 105 box for packing or shipping purposes the front and rear walls 2 and 3 are moved to their proper vertical position, the side walls 4 and 5 are then moved so that they interpose the catches 11 and the flanges 9 and 10. 110 Thus it will be seen that the walls 2, 3, 4 and 5 are locked in their proper position by

means of the flanges 9 and 10 and catches 11. The abutting terminals of the flanges 9 and 10 are rounded as at 12 thus permitting the movement of the flanges 9 carried by the walls 2 and 3 without interference by the flanges 10.

A square nut 13 is countersunk centrally of the bottom wall 1 in a square opening formed therein. A washer 14 is mounted 10 upon the upper face of the nut 13 so that the opening therein alines with the opening in the nut. This washer 14 is countersunk centrally of the ends of a reinforcing strip 15 thus holding the washer firmly in place. 15 The reinforcing strip 15 is bolted or otherwise suitably secured to the upper surface of the bottom wall 1 transversely of the strips 7 and 8 so that its terminals abut the same. An opening 16 is formed through 20 the reinforcing strip 15 and alines with the opening in the washer 14 and nut 13. A suitably elastic strap 17 is secured terminally in any suitable manner to the reinforcing strip 15 and bottom wall 1 and serves to 25 hold the short screw 18 that is used for securing the box in a folded position, when the box is in its open position and ready for shipment and the screw 18 not in use. When the device is in its folded position the 30 screw 18 is inserted through a countersunk opening 19 in the box lid or top designated 20 as an entirety and is turned in the nut 13 thus securing the box in a folded position.

A pair of reinforcing strips 21 are secured 35 to the bottom wall 1 adjacent the front and rear edges thereof and serve to reinforce the strips 7 and 8 as well as firmly hold the reinforcing strip 15 in its proper position.

The top 20 is of the same material as the 40 bottom, side, front and rear walls of the box. A plurality of molding strips 22 are secured to the edges of the top 20 lie flush with the outer surface thereof and extend downwardly beneath the under surface and 45 forms flanges. These molding strips 22 also serve to reinforce and protect the lid 20. A groove 23 is formed in the under surface of the lid 20 about the edges thereof in spaced relation to the under side of the 50 molding strips 22. Strips of beading 24 are suitably mounted within the grooves 23 and when thus disposed form a groove 25 adapted to receive the upper edges of the walls 2, 3, 4 and 5, when the box is in 55 its open position. A reinforcing strip 26 is bolted or otherwise suitably secured to the under face of the lid 20 and carries a washer 27 so that the opening therein alines with the opening 19 in the lid.

60 The ventilating means afforded by the lid 20 consists of four blocks 28 that are bolted or otherwise suitably secured in spaced relation to the under side of the lid 20. The blocks 28 are considerably spaced from the 65 edges of the lid 20 and have secured or glued

to their under faces a section of card-board 29 or other suitably thin material. This section 29 is arranged upon the blocks 28 so that the edges thereof are flush with the sides of the blocks. A plurality of ventilating openings 30 are formed through the lid 20 within the area of the section 29 carried there beneath. It will thus be seen that the card-board section 29 in being supported by the blocks 28 in spaced relation to the 70 under side of the lid 20 and that the ventilating openings 30 formed in the lid provide for an efficient ventilation of the box. The card-board section 29 is provided centrally with an opening 31 through which is adapted to be inserted a large screw 32 and the small screw 18. The large screw 32 is to be inserted through the opening 19 in the lid 20 and turned in the nut 13 carried by the bottom wall 1, when the box is in its open 75 position and serves to reinforce and hold the box in a rigid manner when in an open position.

In Figs. 4 and 8, which illustrate a slightly modified form of my invention, the 80 box consists of hinged sections 33 and 34 which comprise the walls of the box. The construction and arrangement of the modified form with the exception of the hinged sections 33 and 34 is identical to the construction of my preferred form of box. The 85 box of my modified form is particularly adapted for shipping purposes where articles of a heavy nature are used. The hinged sections 33 and 34 fold upon each 90 other and then upon the hinged sections of the other walls of the box as will be clearly seen with reference to Fig. 8. A plurality of angle bars 35 are secured to the several 95 edges of the box of my modified form by bolts or other suitable fastening means and serve to protect the edges of the box and as a reinforcing means.

In reduction to practice, I have found that the form of my invention, illustrated in the 100 drawings and referred to in the above description, as the preferred embodiment, is the most efficient and practical; yet realizing that the conditions concurrent with the adoption of my device will necessarily vary, 105 I desire to emphasize the fact that various minor changes in details of construction, proportion and arrangement of parts may be resorted to, when required, without sacrificing any of the advantages of my invention, as defined in the appended claims.

What is claimed is:—

1. A collapsible box comprising a bottom wall, side walls hingedly secured to said bottom wall, strips secured to the front and rear edges of said bottom wall, front and rear walls hingedly secured to said strips, flanges carried at the terminals of said strips and the front and rear walls, said flanges rounded at their adjacent terminals, a catch 110

carried terminally of each of the front and rear walls in spaced relation to said flanges, a screw adapted to be inserted through said lid and have threaded engagement with the bottom wall.

2. A collapsible box comprising a bottom wall, side walls hingedly secured to said bottom wall, said side walls comprising a pair of hinged sections, strips secured to the front and rear edges of said bottom wall, front and rear walls hingedly secured to said strips, said front and rear walls comprising hinged sections, angle bars secured to the edges of said walls, a lid for said box, ventilating means carried by said lid upon the under side thereof, said lid having a plurality of ventilating openings formed therethrough within the area of said ventilating means, a nut carried by said bottom wall centrally thereof, a reinforcing strip mounted upon said bottom wall and holding said nut in place and a screw adapted to be inserted through said top and the reinforcing strips and have threaded engagement with said nut.

3. A collapsible box comprising a bottom wall, side walls hingedly secured to said bottom wall, strips secured to the front and rear edges of said bottom wall, front and rear walls hingedly secured to said strips, 30 said walls adapted to be folded to lie against said bottom wall, a nut countersunk in the upper surface of said bottom wall, a washer mounted upon said nut, a reinforcing strip mounted upon said washer and secured to 35 said bottom wall, a lid for said box having an opening formed centrally therethrough and a screw adapted to be inserted through said opening in the lid, the reinforcing strip and washer and have threaded engagement 40 with the nut in said bottom wall and means carried by said front and rear walls for locking the side walls in open position.

In testimony whereof I affix my signature in presence of two witnesses.

SIMON FINKELSTEIN.
